INVENTOR:

Herbert Smith,

By his Attorneys,

Arthur G. Fraser # UNITED STATES PATENT OFFICE.

HERBERT SMITH, OF NEW YORK, N. Y.

DESIGN FOR A PENCIL-POINT PROTECTOR.

SPECIFICATION forming part of Design No. 27,818, dated November 9, 1897.

Application filed August 24, 1897. Serial No. 649,398. Term of patent 7 years.

To all whom it may concern:

Be it known that I, HERBERT SMITH, a citizen of the United States, residing in the city, county, and State of New York, have invented 5 a certain new and original Design for Pencil-Point Protectors, of which the following is a specification, reference being had to the accompanying drawings, forming part hereof, in which—

10 Figure 1 is an elevation of my point-protector, showing it applied to a pencil. Fig. 2 is a perspective view of the point-protector alone.

15 My new design for a point-protector is characterized by an approximately cylindrical portion *a*, fitting over the pencil and having the usual split *b*, the cylindrical portion being very slightly swelled at *c* and contracted at *d*, where it is formed with a bead *e*, and from this 20 contraction upward it is extended, of a consid-

erably-reduced diameter, at *f* to its apex *g*, the portion *f* being conoidal, tapering slightly and with a very slightly curved outline to the rounded apex.

The principal distinguishing feature of my 25 design is the combination of the main portion *a*, of full diameter, with the reduced portion *f* (which receives the pencil-point) and the intervening contraction *d*.

I claim as my invention—

30 The design for a pencil-point protector substantially as herein described and as shown in the accompanying drawings.

In witness whereof I have hereunto signed my name in the presence of two subscribing 35 witnesses.

HERBERT SMITH.
